DUAL PLUG IGNITION SYSTEM

Elmer W. Lautenberger, Schenectady, N. Y., assignor to General Electric Company, a corporation of New York

Application July 6, 1950, Serial No. 172,337

1 Claim. (Cl. 123—148)

1
This invention relates to ignition systems and more particularly to such systems as are required to be operable many miles above the earth such as in jet engines for aircraft.

With the advent of jet aircraft capable of attaining higher and higher ceilings into the cold rarified regions above 40,000 feet, there has arisen the problem of restarting combustion in the chambers of jet engines. At altitudes above this region it has been demonstrated that conventional ignition systems almost invariably fail to "light their burners" and, numerous attempts to overcome this restart difficulty have failed.

Indications have been that a larger spark gap improves altitude starting performance. However, there is a practical limit to which a spark gap can be lengthened and this depends upon the available output voltage of the ignition unit which units already produce the maximum line to ground voltages that it is practical to impress on high-tension ignition cables which are also already stressed well beyond their corona level. The lack of a practical ignition system due to the foregoing problem has heretofore imposed a serious limitation on the development and operation of jet engines otherwise capable of high altitude flying.

It is an object of this invention to provide an ignition system which overcomes the foregoing restart difficulties at high altitudes and yet which is simple and positive in operation.

It is a further object of this invention to provide an ignition system which is particularly adapted for high altitude jet engine aircraft.

Still another object of this invention is to provide an ignition system which will operate at both low and high altitudes while at the same time providing the type of electrical discharge required at the higher altitudes to initiate combustion.

A still further object of my invention is to provide an ignition system in which two separate spark plugs are used in the same combustion chamber, neither of which plugs have a ground electrode.

A still further object of this invention is to provide an ignition system which will not stress the system insulation beyond present maximum practical levels and yet will provide twice the usually available voltage to jump the spark gap.

A still further object of this invention is to provide a system capable of firing a spark gap roughly twice as large as the maximum gap that it is practical to fire with a conventional system.

Still another object is to provide an electrical discharge for initiating combustion which has

2
greatly increased capacitive and inductive components and consequently provides greater power and energy.

According to my invention, I provide an ignition system which comprises two separate spark plugs, each of which plugs are oppositely disposed in the same combustion chamber and have a single ungrounded electrode. A high tension circuit is connected between the two electrodes and the latter are energized simultaneously, the polarity of the voltage impulses on one electrode being positive and the polarity of the voltage impulses on the other electrode being negative so that the electrical discharges take place in a wide gap between the two spark plugs.

The invention will be more fully understood by referring now to the accompanying drawing of a diagrammatic representation of my improved ignition system as applied to one of the combustion chambers of a jet engine.

The drawing shows a cross-sectional view of a combustion chamber 1 which has an inner liner 2. This chamber represents one of a plurality of combustion chambers which are normally annularly disposed within the outer periphery of a conventional jet engine.

Projecting into the combustion chamber are two spark plugs 3 and 4 which are of identical construction. Looking at spark plug 3 it will be seen to comprise an elongated high voltage electrode 5 which is centrally disposed in a ceramic insulator 6 within a metal housing 7 having a mounting flange 8 whereby the spark plug 3 may be keyed and secured to the combustion chamber. It will be noted that my spark plug has a single extended high voltage electrode but no ground electrode. The upper portion above the mounting flange may be of any suitable conventional construction.

As mentioned above, spark plug 4 is similar in construction to spark plug 3 and they should be cooperatively located so that the inner extremities of their centrally disposed electrodes extend toward each other irrespective of the axial disposition of their housing 7 in the chamber.

Spark plugs 3 and 4 are energized by ignition coils 10 and 11. Coil 10 has a primary or low tension winding 12 and a secondary or high tension winding 13 and one end of each of these windings are connected together, the opposite end of high tension winding 13 being connected by a cable 14 to the single electrode 5 of spark plug 3.

Ignition coil 11 is similar to the one just described, it also comprising a low tension winding 15 and a high tension winding 16, having one end

of each connected together, the other end of the high tension winding 16 being connected via cable 17 to the single electrode 9 of spark plug 4. The two high tension windings 13 and 16 are serially connected together at 18.

A source of sparking voltage for my system may be obtained in a number of different ways known to the art. For purposes of illustrating a completely operative system, I have shown a vibrator type battery operated system which uses a conventional electrical circuit except that an additional ignition coil, and a capacitor having twice the usual capacity, have been added to the circuit as will hereinafter be described.

As shown in the drawing, a battery 19 is connected in series with a switch 20, ignition coil primaries 12 and 15, and with a circuit comprising the parallel arrangement of a capacitor 21 and a vibrator 22. The ignition coil primaries have approximately two-thirds the number of turns normally employed in a conventional single ignition coil circuit. One side of the battery 19 is connected to one end of ignition coil primary 15 and grounded at 24'.

The vibrator 22 is seen to comprise a reed 23 at the top of which is mounted an armature 24. In addition, the reed 23 carries two pairs of contacts 25 and 26 which operate with the reed as will be explained. When the reed 23 is at rest, contacts 25 are closed, and a circuit may be traced through an electromagnet 27 to ground.

With the foregoing understanding of the elements and their organization, the operation of my invention will be readily understood from the following explanation. When the switch 20 is closed, current will flow through closed contacts 25, electromagnet 27 and to ground thus causing the armature 24 to be drawn to the right thereby closing contacts 26. This will cause current to build up in the ignition coil primaries 12 and 15. After contact has been established at 26, the contacts at 25 will open and the electromagnet 27 will be de-energized and the reed 23 will return to the left position. This cycle will continue and current flow to the ignition coil primaries 12 and 15 will be alternately established and interrupted. With each interruption, the flux produced by current in the ignition coil primaries, collapses at a very rapid rate. Much of this flux links the ignition coil secondaries 13 and 16 as well as the primaries 12 and 15. The rapid rate of decay of flux in each of these ignition coils induces voltages in both the primary and secondary windings. Because the secondary windings have more than one hundred times as many turns as the primary windings their voltages are correspondingly very much higher. As shown in the drawing, the ignition coils are connected to produce voltages in coils 13 and 16 which are 180° out of phase so that spark plug 3 will be energized by a high voltage having a polarity opposite to that of the high voltage supplied to spark plug 4. This results in developing a voltage which is twice as great as the voltage developed in a conventional single ignition coil system yet without any increase in the line to ground voltage stress on ignition cables 14 and 17.

The opening of contacts 26 causes capacitor 21 to be switched into the primary circuit and this capacitor thereupon becomes charged by the voltage which was induced in primary coils 12 and 15. Due to the secondary capacitance of the cables and spark plugs, they also will be charged by the voltage induced in secondary coils 13 and 16. At the instant that the voltage between elec-

trodes 5 and 9 reaches the breakdown potential of the gap a high frequency spark will jump the gap and dissipate the energy stored in the secondary capacitance of the system. It will be appreciated that the use of a second high tension cable and spark plug in my system has doubled this capacitance and energy in the spark compared to that obtainable from a conventional single spark plug system. Following the discharge of secondary capacitance, the energy of the primary capacitor is dissipated in the spark at a much lower frequency. This capacitive component is also greatly increased in my system since it will be recalled that the addition of a second ignition coil to the circuit permits the use of a primary capacitor having twice the electrical size. Finally, the inductive component or arc which follows the spark is also greatly increased inasmuch as it is produced by the inductive energy of two ignition coils rather than one as in conventional systems.

Thus, the system herein described not only provides twice the output voltage usually available and thus makes it possible to substantially double the gap length between electrodes without causing any increase in the electrical stress on the system insulation, but, furthermore, the energy of each electrical discharge across the gap is greatly increased by virtue of the larger capacitive and inductive components of the spark and arc. These advantages obtained when using my ignition system have been found by wind tunnel test of a full scale jet engine to result in greatly improved high altitude starting performance.

In Patent 2,447,782 to Welge, there is shown an ignition system directed to the elimination or suppression of radio frequency interference which results from their operation in internal combustion engines. The Welge patent discloses a system in which a single spark plug has two electrodes both of which are insulated from ground and fed by a balanced two wire system. It will be evident upon examination, however, that this system has only a superficial resemblance to my invention since it requires a close interrelation of leads to the spark plug and this would increase rather than improve the severe corona and insulation breakdown problems encountered at high altitudes. In my system the cables to the plugs are purposely widely separated which construction is just opposite to that of the Welge patent which teaches the balancing out of radio interference voltages. The present invention requires electrodes to be widely separated and, in fact, to be removed outside the bounds of the same spark plug in order to provide a greater capacitive component. It will be appreciated, therefore, that the above patentee's system is not capable of producing as long and as hot a spark at high altitudes.

It should be understood that my system will operate at sea level as well as at high altitudes and this will depend partly upon the choice of the gap distance. For practical purposes, and to insure firing at sea level conditions, I prefer to set the gap between electrodes at about one-half inch to insure positive starting throughout the altitude range of the aircraft although my system will operate with gap settings several inches long at altitudes in the order of 50,000 feet provided adequate insulator flashover distance is built into the exposed end of the spark plug.

Although a particular embodiment of my invention has been illustrated and described, modi-

fications thereof will readily occur to those skilled in the art. It should be understood, therefore, that the invention is not limited to the particular arrangement disclosed but that the appended claim is intended to cover all modifications which do not depart from the true spirit and scope of my invention.

What I claim as new and desire to secure by Letters Patent of the United States is:

In an ignition circuit for a jet engine combustion chamber, a pair of separate single-electrode spark plugs adapted to project into said chamber in opposing relation to define a spark gap therebetween, each said plug including means insulating the plug electrode from said chamber and the external ends of said plug electrodes being widely spaced apart, a pair of separate ignition transformers each having a low voltage primary winding and a high voltage secondary winding, a common connection connecting said primary windings and said secondary windings respectively in back-to-back series circuit relation thereby to provide at opposite ends of said secondary windings instantaneous voltages of opposite polarity, means grounding said wind-

ings at a point electrically adjacent said common connection, and a pair of insulated high-voltage lead wires positioned remotely with respect to each other and connecting said opposite ends of said secondary windings to said plug electrodes respectively, whereby said plug electrodes are supplied with voltages of opposite polarity with respect to ground and the voltage applied across said gap is substantially greater than the line-to-ground voltage at any part of said circuit.
